LEAPING FIGURE TOY

Renold A. Miskin, Clearfield, Utah, and Judson N. Suddarth, Seattle, Wash.; said Suddarth assignor to said Miskin

Application January 17, 1950, Serial No. 139,088

6 Claims. (Cl. 46—129)

1

The invention relates to figure toys, and has for its principal object the provision of an animal-simulating toy which is susceptible of voluntary actuation to produce leaping or jumping movements thereof.

Another object of the invention is to provide an effective actuating mechanism for such a toy, whereby a lifelike leap clear of the supporting surface may be imparted to it with a minimum of effort, well within the capability of a relatively small child. Furthermore, the construction is such as to tend to prevent tipping over of the toy, either at the beginning or at the conclusion of the movement.

While for purposes of disclosure of the principles of the invention a frog has been chosen for illustration in the accompanying drawing forming a part of this specification, the genus of the animal simulated is not important and the body form may be that of any appropriate member of the animal kingdom.

In the said drawing, in which like reference characters designate like parts in all the views—

Figure 1 is a side elevational view of a toy constructed and arranged in accordance with the invention;

Fig. 2 is a bottom plan view, partly broken away and in section, of the toy shown in Fig. 1;

Fig. 3 is a longitudinal vertical sectional view of the toy, with the parts being shown in the positions they normally occupy when the toy is at rest upon a supporting surface;

Fig. 4 is a view similar to Fig. 3, showing the parts in the positions assumed in the course of a leap;

Fig. 5 is an enlarged side elevational view of the lower portion of the actuating cylinder and the parts associated therewith; and

Fig. 6 is an end view of the parts shown in Fig. 5.

Referring to the drawing in greater detail, the toy there shown comprises a hollow body 10 having the general conformation and external markings of the animal simulated, in this case a frog. Curved elements 11 simulating the front legs and feet of the animal are fixedly attached to the forward sides of the body and extend laterally, downwardly and forwardly from the points of attachment to engage the ground or other supporting surface. Elements 12 simulating the upper or femoral portions of hind legs are fixedly secured to and extend substantially horizontally along the rearward sides of the body, and to the rearward end of each such element there is hingedly attached as at 13 the rearward end of an

2

element 14 simulating the lower or tibial portion of a hind leg. As will be clear from Fig. 1, the tibial elements 14 normally underlie the femoral elements 12, in engagement with the supporting surface, and the forward ends 15 of the elements 14, which are formed to simulate the hind feet, are disposed adjacent the mid portion of the body.

The several leg elements 11, 12 and 14, along with the body 10, may conveniently be constructed of soft rubber or appropriate molded plastic material. While for the purpose of facilitating manufacture the fore leg elements 11 and the femoral elements 12 may be formed as members 15 separate from the body, to which they are subsequently cemented or otherwise fixedly attached, if convenient the members 10, 11 and 12 may be molded as an integral unit. When the parts are of soft rubber or like yieldable material, the hinging action between the upper and lower hind leg elements 12 and 14 may be secured solely through flexing or stretching of the material at or adjacent the points 13.

To the lower face of the foot portion 15 of each tibial element 14 there is cemented a pad 16 of sponge rubber or the like. The under faces of these pads frictionally engage the ground or other supporting surface 18 and provide an anti-slipping contact therewith which is of material assistance in securing the desired leaping action through the air, completely clear of the supporting surface. The foot portions 15 are of reduced thickness or otherwise formed to provide flexibility at 17 along a transverse plane coincident with the rearward edge of the pads 16, whereby a hinging action may take place at this point which permits the pads to remain in flat contact with the surface 18 during the initial portion of a leap and tends to prevent the toy from nosing over forwardly. In some cases the entire tibial elements 14 may be formed of sponge rubber, in which event separate pads 16 of such material of course need not be used.

Within the cavity or chamber 19 defined by the walls of the body 10 there is mounted a fluid pressure cylinder 20. As will be readily understood from the drawing, the axis of this cylinder is disposed in substantially the plane of the longitudinal axis of the animal and at an inclination of approximately 30° to the vertical when viewed as in Figs. 3 and 4; and the upper end of the cylinder, which is closed, is provided with a ported boss 21 to which is connected one end of a flexible tubing 22 which extends through the wall 55 of the body 10 and has its other end connected

to a resilient bulb or equivalent manually operable fluid pressure inducing device 22'. The cylinder 20 is supported within the cavity 19 by means of a transversely extending member 23, conveniently comprising a curved wire, the mid portion of which is soldered, welded or otherwise rigidly attached to the cylinder at 24. The lateral portions of the member 23 extend from the cylinder across the cavity 19 to and interiorly of the fore leg elements 11, in which they may be embedded or otherwise attached. The curved wire 23, while rigid enough to provide support for the cylinder 20, is at the same time sufficiently yielding to provide a cushioning action in the fore legs when the toy lands at the conclusion of a leap. The said wire also serves to transmit the impelling force to the body, as will presently appear.

Mounted in the cylinder 20 is a piston structure 26, carried by one end of a piston rod 27 which is slidably received in a bearing sleeve 28 supported at the open lower end of the cylinder by the crossed U-shaped wires 29, the cross bars of which are soldered or welded to the sleeve while their legs are soldered or welded to the exterior of the cylinder wall, as will be clear from Figs. 5 and 6. A helical compression spring 30 is interposed between the piston 26 and the grid wires 29, and tends to maintain the parts in the positions shown in Fig. 3, with the piston in the upper end of the cylinder. Below the bearing sleeve 28 the piston rod 27 extends through an aperture 31 formed in the lower wall of the body 10, and the lower end of said rod is provided with a transverse hole which journals the mid portion of a transverse wire 32 extending beneath the body 10 to the forward parts of the hind foot portions 15 and anti-slipping pads 16 to which the wire ends are attached.

The operation of the toy as thus far described will be readily understood. With the simulated animal resting upon the ground or other supporting surface 18 as shown in Fig. 1, upon manually squeezing the bulb 22' the fluid therein will be compressed and forced through the tube 22 to the upper end of the cylinder 20, above the piston 26. With the anti-slipping members 16 in engagement with the surface 18 and through the transverse connecting member 32 serving as thrust-taking members or anchors for the piston rod 27 and piston 26 to restrain movement thereof, the increased pressure in the cylinder above the piston causes axial movement of the cylinder upwardly and forwardly, which motion is transmitted through the supporting wire or member 23 to the body 10. As a result the body is propelled upwardly and forwardly, with the relative movement between the cylinder and piston causing the hind leg elements 14 to assume the position shown in Fig. 4, at which time the momentum is such as to cause the entire toy to bodily leave the supporting surface and follow a trajectory which carries it forwardly a foot or more from the starting point in close simulation of the leap of a real animal.

Ordinarily the manual pressure is exerted on the bulb 22' only momentarily, i. e. the bulb is given a quick squeeze and released, and upon such release the fluid pressure in the cylinder 20 above the piston 26 falls to normal and the spring 30 returns the parts to the Fig. 3 positions by the time the leap is completed. A landing under such conditions is effected with practically no tendency of the toy to tip over; and even if the bulb is not released prior to landing, so that the hind leg elements 14 are still extended at such

time, there still is substantially no tipping tendency. If the bulb be pressed quite slowly so that the build-up of pressure in the cylinder is relatively slow, the hind leg elements 14 may be actuated to the Fig. 4 position without the toy acquiring sufficient momentum to leave the surface 18, and as a result it will merely inch along such surface.

The widespread fore legs 11, extending well forwardly of the center of gravity, coupled with the fact that the propulsive force is applied to the body in a direction more upwardly than forwardly, tend to prevent the animal from tipping or nosing over forwardly when the bulb is pressed; and since the parts are so arranged that the center of gravity lies substantially in the plane of the longitudinal axis of the toy, and since the propulsive force is applied to the body symmetrically on opposite sides of said plane, there is substantially no tendency of the toy to tip sidewise.

Toys constructed as above described will function quite satisfactorily to give life-like leaps of a foot or more, depending upon the size and weight of the parts. However, the length of the leap may be materially increased by the use of an action delaying device in conjunction with the cylinder and piston, and one form of such a device has been illustrated in the present drawing. As here shown, it comprises a U-shaped wire member 35 disposed at the lower end of the cylinder 20, with the extremities of its legs soldered or welded as at 36 to the cylinder wall, and its cross bar extending across the open end of the cylinder in position to engage a small arc of the end edge of the piston rod 27 when the latter is in the position shown in Figs. 3, 5 and 6. The restraint thus imposed upon movement of the cylinder 20 relative to the rod 27 and piston 26 enables the building up of some pressure above the piston in addition to that necessary to overcome the action of the spring 30, and when the desired build-up has been attained the resilience of the legs of the latch member 35 permits the cross bar of such member to be forced upwardly 45 out of engagement with the edge of the rod end, whereupon the cylinder will ascend with something of a snap action. As above indicated, this will materially increase the length of the leap.

In the case of some animals the cylinder-supporting and force-transmitting member 23 may be attached directly to the walls of the body adjacent the cylinder, instead of extending into and being secured to the fore legs; and if the body cavity 19 is small enough for the body walls to directly engage and support the cylinder, the member 23 may be dispensed with for this purpose.

While one form of the invention has been illustrated and described, it will be obvious that those skilled in the art may vary the details of construction as well as the precise arrangement of parts without departing from the spirit of the invention, and therefore it is not wished to be limited to the above disclosure except as may be required by the appended claims.

What is claimed is:

1. A leaping figure toy comprising a hollow animal-simulating body having hingedly connected leg elements provided with hingedly connected foot portions having anti-slipping surfaces frictionally engageable with a supporting surface; a fluid pressure cylinder mounted within the body; a piston in said cylinder, having a piston rod projecting therefrom; thrust transmitting connections between said piston rod and foot

portions; means for intermittently supplying fluid under pressure to the cylinder whereby to induce movement thereof and of the body relative to the piston to project the toy through the air, clear of the supporting surface, the hinge connections between said leg elements and foot portions enabling the latter to remain in flat anti-slipping contact with the supporting surface during the initial movements of the body and leg elements; and means for restoring the initial relative positions of the cylinder and piston upon relief of the fluid pressure in the cylinder.

2. A leaping figure toy comprising a hollow animal-simulating body having fixedly connected front leg elements and hingedly connected hind leg elements adapted to rest upon a supporting surface; a forwardly inclined fluid pressure cylinder disposed in the cavity of said hollow body; a resilient supporting member attached to said cylinder and extending therefrom into said front leg elements; a piston in said cylinder, having a piston rod extending to the exterior of the body adjacent said hind leg elements; a member extending transversely below the body and connecting the piston rod with said hind leg elements; resilient pads carried by the hind leg elements, having anti-slipping surfaces frictionally engageable with the supporting surface; a resilient bulb connected to the cylinder for intermittently supplying fluid under pressure thereto above the piston, whereby to induce axial movement of the cylinder relative to the piston and thereby bodily propel the toy upwardly and forwardly in a trajectory clear of the supporting surface; and means for restoring the initial relative positions of the cylinder and piston upon relief of the pressure in the cylinder.

3. A leaping figure toy comprising an animal-simulating body adapted to rest upon a supporting surface; a longitudinally inclined fluid pressure cylinder disposed within and connected to said body; a piston in said cylinder, having a piston rod projecting from the latter; thrust-taking members connected to said piston rod and having anti-slipping faces frictionally engageable with said supporting surface; manually operable fluid pressure inducing means connected to the cylinder for intermittently supplying fluid under pressure thereto above the piston, whereby to induce movement of the cylinder and body relative to the piston and thereby bodily project the toy through the air in the direction of the cylinder axis, clear of the supporting surface; an action-delaying device restraining movement of the cylinder until a predetermined pressure is built up therein; and means for restoring the initial relative positions of the cylinder and piston upon relief of the pressure in the cylinder.

4. A leaping figure toy comprising an animal-simulating body adapted to rest upon a supporting surface; a fluid pressure cylinder disposed within and connected to said body, the axis of said cylinder extending in the direction of the intended leap; a piston in the cylinder, having a piston rod projecting from the latter; thrust-taking members connected to said piston rod and having anti-slipping surfaces frictionally engageable with said supporting surface; means connected with the cylinder for intermittently supplying fluid under pressure thereto to one side of the piston, whereby to axially move the cylinder relative to the piston and thereby bodily

propel the toy in a trajectory clear of the supporting surface; an action-delaying latch carried by the cylinder and engageable with the piston rod to temporarily restrain movement of the cylinder until a predetermined pressure has been built up therein; and means for restoring the initial relative positions of the cylinder and piston upon relief of the fluid pressure in the cylinder.

5. A leaping figure toy adapted to be propelled upwardly from and clear of a supporting surface, said toy comprising an animal-simulating body; a rectilinear cylinder mounted within and connected to said body, the axis of said cylinder being disposed at a substantial angle to the horizontal and extending in the direction of the intended leap; a piston in the cylinder, having a piston rod projecting downwardly from the latter; thrust-taking means connected to said piston rod and disposed to engage the supporting surface; means connected to the cylinder for intermittently creating a pressure differential therein on opposite sides of the piston, whereby to force said thrust-taking means against the supporting surface and through reaction to induce rectilinear movement of the cylinder and body upwardly in the direction of the cylinder axis, thus bodily propelling the toy upwardly clear of said surface; and means for restoring the initial relative positions of the cylinder and piston upon termination of said pressure differential in the cylinder.

6. A leaping figure toy adapted to be propelled upwardly from and clear of a supporting surface, said toy comprising an animal-simulating body; a rectilinear fluid pressure cylinder mounted within and having force-transmitting connections with said body, the axis of said cylinder being disposed at a substantial forward and upward angle to the horizontal and extending in the direction of the intended leap; a piston in the cylinder, having a piston rod projecting downwardly and rearwardly from the latter; thrust-taking means connected to the projecting portion of said piston rod and disposed to engage the supporting surface rearwardly of said cylinder and body connections; means connected to the cylinder for intermittently creating a fluid pressure differential therein on opposite sides of the piston, whereby to force said thrust-taking means against the supporting surface and through reaction to induce rectilinear movement of the cylinder and body upwardly in the direction of the cylinder axis, thus bodily propelling the toy in a trajectory clear of said surface; and means for restoring the initial relative positions of the cylinder and piston upon termination of the pressure differential in the cylinder.
